ATTORNEY

UNITED STATES PATENT OFFICE

GUSTAVO TRIFARI, OF BROOKLYN, NEW YORK, ASSIGNOR TO TRIFARI, KRUSSMAN & FISHEL, INC., OF NEW YORK, N. Y., A CORPORATION OF NEW YORK

CLIP BROOCH

Application filed February 17, 1932. Serial No. 593,437.

The object of the present invention is to provide a combined brooch and clip of a novel and decorative form, the brooch comprising two separable members detachably mounted upon a pin bar, either of which is 5 adapted to be mounted upon a hinged clip bar for use as a clip.

The invention will be described with reference to the accompanying drawing in which

10 Fig. 1 is a plan view of the assembled brooch.

Fig. 2 is an enlarged side elevation of the device.

15 Fig. 3 is a rear plan view of the device enlarged and one element of the brooch separated.

Fig. 4 is a transverse section on the line 4—4, Fig. 3.

20 Fig. 5 is a side elevation of one member of the brooch held by the clip member against the face of a fabric and showing in dotted lines the action of the toothed element of the clip bar.

25 Fig. 6 is a side elevation of the clip shown in Fig. 5.

Fig. 7 is a front elevation of the same.

Fig. 8 is a plan view of the brooch element shown in Fig. 5.

30 Fig. 9 is a bottom plan view of the hinged clip bar structure shown in Figs. 5, 6 and 7.

A front view of one of the brooch elements is shown in Fig. 8 and the rear view thereof to the right of Fig. 3. The elements assembled are shown in Figs. 1 and 2.

35 Each brooch element comprises a metal frame 1 decorated on its front face, as by the insertion of brilliants or other stones, by enameling, by filigree work, etc.

40 Each brooch element is formed with an outer edge 1a and a straight wall inner edge 1ax.

45 Secured to the rear face of each element near the inner edge is a loop 2 and between the loop and the outer edge of the element the latter carries a headed stud 3 which, if desired, may be reversed in position and may be modified as to form.

When the device is used as a brooch, it is 50 carried by a pin-holding frame, and when one

of the ornamental elements is used as a clip, it is carried by a hinged frame which in its function of holding the member 1 is identical with the pin-holding frame.

The pin-holding frame is clearly illustrated in Fig. 3. It consists of opposed spring-like sections 4, 4x connected by a section 10 having opposed rectangular projections, each projection being adapted to enter the loop 2 attached to one of the ornamental members 1. The free end of each member 4, 4x is provided with opposed spring prongs 4xx which are sufficiently spaced to receive the stem of a headed stud 3, the inner surface of each spring prong being curved to conform with the rounded surface of the stem. Each set of prongs 4xx will be spaced slightly less than the diameter of the stud stem so as to press upon the same when it is in position. Thus, the spring prongs will act to hold member 1 by frictional engagement with the stem of the stud and by abutment with the head of the stud.

Member 4 of the pin-holding frame will have pivotally attached thereto a pin 5 which pin is adapted to be held by a suitable catch member 6 carried by member 4x, the construction of the catch member forming no part of the present invention and being diagrammatically shown rather than shown in detail.

75 The hinged clip frame is formed of two sections 7 and 7x connected by hinge pin 8 and, as shown more particularly in Fig. 7, the member 7 is formed with a spring extension a engaging a post 7xx carried by member 7x for receiving the hinge pin 8. Member 7x is provided with engaging means for headed stud 3 of the same form as that provided on the pin frame and also with a loop-entering member, for loop 2, and, therefore, the same 80 numerals for these parts are used in Fig. 9 as in the figures showing the pin frame.

95 Member 7 of the clip frame is provided with pins b the action of which is shown in Fig. 5 wherein by dotted line position member 7 is shown in initial position, then moved downward partly toward the fabric c, then into engagement with the fabric, so as to hold the clip engaged therewith, the pins entering the fabric.

From the above, it will be seen that the two horizontal members 1, 1, Fig. 1 are adapted to lie in edge juxtaposition, each carrying a holding element, to wit, headed stud 3. The frame, illustrated more particularly in Figs. 2, 3 and 4, is provided with means for engaging each of the holding elements, said means being the spring prongs 4xx, the frame having a pin for securing it to a fabric. It will also be seen that a hinged clip frame 7 is adapted to receive either of said horizontal members 1, the clip frame having spring prongs 4xx which interlock with the appropriate stud 3 so as to support member 1 independently of the first-named frame.

Having described my invention, what I claim and desire to secure by Letters Patent, is as follows:—

1. A combined brooch and clip comprising an ornamental member and a headed stud and loop carried by the latter in spaced position in combination with a frame, and means for securing the frame to a fabric, the frame having at one end spring prongs adapted to engage the headed stud and also having rearwardly of the spring prongs a projection adapted to enter the loop.

2. An article of jewelry comprising two ornamental members adapted to lie in edge juxtaposition and in such position to form the ornamental elements of a brooch and a loop and a headed projection carried by each of said ornamental members, in combination with a frame having at each end thereof spring prongs adapted to engage the headed projection and having rearwardly of each end a projecting member adapted to enter the loop of an ornamental member, said frame having means for attaching the same to a fabric.

In testimony whereof, I have signed my name to this specification.

GUSTAVO TRIFARI.
